United States Patent Office

Des. 223,128
Patented Mar. 14, 1972

223,128

AIRCRAFT

Harold D. Ulisnik, Trumbull, and Andrew C. Whyte,
Norwalk, Conn., assignors to United Aircraft Corpora-
tion, East Hartford, Conn.

Filed Sept. 30, 1970, Ser. No. 25,679

Term of patent 14 years

Int. Cl. D12—07

U.S. Cl. D71—1

FIG. 1 is a top view of the aircraft;
FIG. 2 is a side view of the aircraft;
FIG. 3 is a front view of the aircraft.

The broken line disclosure of rotors and landing gear
is for illustrative purposes only.

We claim:

The ornamental design for an aircraft, substantially as
shown and described.
